UNITED STATES PATENT OFFICE.

PHYLLIS MARGARET TWIGG, OF VENTNOR, ENGLAND.

DESIGN FOR A HAT STAND.

Application filed April 19, 1927. Serial No. 21,639. Term of patent 14 years.

To all whom it may concern:

Be it known that I, PHYLLIS MARGARET TWIGG, a subject of the King of Great Britain, residing at Ventnor, Isle of Wight, England, have invented a new, original, and ornamental Design for a Hat Stand, of which the following is a specification, reference being had to the accompanying drawing, forming part thereof.

I claim:

The ornamental design for a hat-stand as shown.

In witness whereof, I have hereunto signed my name this 8th day of March, 1927.

PHYLLIS MARGARET TWIGG.
